VAT MOUNTING FOR A PACKAGE CARRIER

Harry S. Drum, Abington, and William H. Jaxheimer and Elmer E. Saalfrank, Philadelphia, Pa., assignors to Smith, Drum and Company, Philadelphia, Pa., a corporation of Pennsylvania

Application October 31, 1939, Serial No. 302,146

3 Claims. (Cl. 68—198)

The present invention relates to package treating apparatus and more particularly to a self controlled stabilized mounting for a package carrier in a treating vat.

5 In the anchoring of a package carrier in a treating vat it has heretofore been the practice to locate the axial support of the carrier in its proper place on the bottom of the vat, then close the vat cover to bring a clamp member 10 over the upper end of the axial support, lock the cover in position, and then turn down the clamp member until the carrier is anchored in place. Not only does this method add to the time required to mount the carrier in the vat 15 but it has the further disadvantage of holding the carrier so rigidly that the action of pressure or the effects of expansion and contraction of the metal cause damage to the carrier parts. In other words the anchored carrier has no 20 chance to flex or compensate for undue pressure or the result of temperature variations.

Some of the objects of the present invention are to provide an improved mounting means for package carriers in a treating vat; to provide 25 a package mounting which automatically compensates for expansion and contraction of its parts under variations of pressure; to provide a package mounting which automatically compensates for pressure within the vat wherein the 30 carrier is located; to provide a means for mounting a package carrier within a vat wherein it becomes unnecessary to manually operate a clamping device to anchor the carrier in position; to provide a carrier mounting mechanism wherein 35 a device of the vat lid clamping type is eliminated; and to provide other improvements as will hereinafter appear.

In the accompanying drawings Fig. 1 represents a sectional elevation of a treating tank 40 showing a package carrier therein equipped with a mounting embodying one form of the present invention; Fig. 2 represents a front elevation of the mounting shown in Fig. 1 but on an enlarged scale; Fig. 3 represents a section on line 3—3 45 of Fig. 2; Fig. 4 represents a section on line 4—4 of Fig. 2; Fig. 5 represents a plan of the device shown in Fig. 2; and Fig. 6 represents a sectional elevation of a vat wherein a different type of carrier is used and a modified form of the 50 invention.

Referring to the drawings, one form of the invention is shown in conjunction with a treating vat 40 and package carrier 41 of the type having a manifold 42 and a plurality of spindles 43 oppositely disposed on the manifold 42. A liquid cir-

culating pipe 44 is axially disposed at the lower side of the manifold 42 and terminates in a tapered fitting 45 for ground joint seating upon the port 46 formed in the bottom of the vat 40. Liquid can thus circulate through the pipe 44 to 5 the manifold 42 and out through the packages 46 which are mounted on the spindles 43 or in the reverse direction as required. It is to be understood that a large number of the spindles 43 are on the manifold of a complete carrier but are 10 here omitted to simplify illustration.

The vat 40 has a cover 47 designed to be clamped to the vat body by well known means to effect a liquid proof seal between the parts. A guide cap 48 is attached to the cover 47 at a 15 point to register with the axis of the carrier when the cover is closed and thus receive the truncated head 49 of the carrier lift rod 50 to position it for engagement by a retainer keeper 51.

In order that the keeper 51 may yield under 20 pressure upon the carrier, a coil spring 52 encircles the projecting end of the keeper 51 and is held under a set compression between a plate abutment 53 and an adjustable follower nut 54. The abutment 53 is a part of a collar 55 which is 25 integral with and forms one end of a loop shaped yoke 56. The opposite end of the yoke 56 is coaxial with the collar 55 and is in the form of an internally threaded hub 57 which screws on the externally threaded sleeve 58 which is a part of 30 the cover 47. A set screw 59 fastens the hub 57 to the sleeve 58. That portion of the keeper 51 which projects into the yoke 56 and is beyond stuffing box 60 is threaded to receive the follower nut 54 which can be adjusted through spanner 35 holes 61 or the like. The stuffing box 60 is adjustable by means of studs 62 so that the packing therein protects the joint between the keeper 51 and the sleeve 58. By the foregoing it will be seen that the keeper 51 is normally pressed 40 against the end of the carrier by the spring 52 but any excess counter pressure will allow the keeper 51 to yield and thereby relieve any abnormal strain on the carrier parts.

To limit the axial movement of the keeper 51, a stop nut 63 is threaded on the keeper end outside of the yoke 56 and by its adjustment determines the projected position of the keeper. A lock nut 64 maintains the set position of the stop nut 63. The extremity of the keeper 51 is of 50 such a shape that it can be engaged by a suitable implement to adjust the keeper relative to the yoke.

In the form of the invention shown in Fig. 6, the vat 40 encloses a package carrier 41 of the 55

type which rests on the bottom of the vat with package spindles 42 rising vertically from the base of the carrier. In this instance the lift member 43 of the carrier is in the form of an open ended tube through which a rod 44 extends for screw threaded engagement with the inlet member 45 of the vat.

In order to yieldingly hold the carrier 41 in place the protruding end of the rod 44 is threaded to receive a follower nut 46 between which and an annular flange 47 there is a coiled spring 48 encircling the rod 44. Radially disposed arms 50 provide means for manually adjusting the nut 46 to place the spring 48 under the required compression for yielding under abnormal conditions within the vat. The flange 47 is arranged internally of the member 43 and is welded or otherwise made fast in order to take the thrust of the spring 48.

In assembling the carrier in the vat reference is had to the form shown in Fig. 1 wherein the spring or yielding unit is screwed tightly on the cover sleeve 30 and locked in place by the set screw 31. With the package carrier in the vat the cover 17 is closed and clamped down tight by the usual clamping bolts, after which the follower nut 25 is fed along the pin 22 until the spring 23 is compressed an efficient working distance. In practice it has been found that a setting of three-quarters of an inch shorter than the free length works very satisfactorily. The stop nut 35 is now adjusted for a clearance of about one-eighth of an inch and is locked by the nut 36.

From the foregoing it will be apparent that in both forms of the invention, shown by way of example, that the carrier, unlike former constructions, is no longer a rigidly connected part of the vat, but the contrary, while having sufficient rigidity to maintain the carrier operatively positioned in the vat, has a planned flexibility to permit a relative movement between the two units when necessary. Thus in case the pressure of steam in the vat becomes abnormal, and such as might distort the carrier parts, the action is automatically compensated by the yielding of the

spring which thus serves to absorb injurious movement. The same action takes place if the movement is caused by the expansion and contraction of the parts under variation of pressure.

Having thus described our invention, we claim: 5

1. In a package treating apparatus, the combination of a vat, a package carrier, a lifting member on said carrier, a clamping pin passing through said vat to engage said member, a yoke attached to said vat to form a bearing for said pin, a spring coacting with said yoke and pin, and means to adjust the tension of said spring. 10

2. In a package treating apparatus, the combination of a vat, a yarn package carrier in said vat having an axially disposed upwardly directed extension, a clamping pin extending through the top of said vat in sliding relation thereto and in co-axial relation to said extension, a yoke attached to said vat and forming upper and lower bearings for said pin, said pin having an upper 20 screw threaded portion, a spring coiled about said pin, a follower threaded on said pin to compress said spring and hold said pin against the end of said extension with a selected pressure, and a stuffing box for preventing leakage about the portion of said pin traversing said vat.

3. In a package treating apparatus, the combination of a vat, a yarn package carrier in said vat having an axially disposed upwardly directed extension, a clamping pin extending through the top of said vat in sliding relation thereto and in co-axial relation to said extension, a yoke attached to said vat but removable as a unit, upper and lower bearings on said yoke for guiding said pin, an upper abutment plate on said yoke, a 35 spring coiled about said pin and seating against said plate, a follower threaded on said pin to engage the free end of said spring and compress it against said abutment plate and thereby hold said pin against the end of said extension, and 40 adjustable means to limit the projected position of said pin.
